UNITED STATES PATENT OFFICE.

FRED W. McARDLE, OF BOSTON, MASSACHUSETTS.

FURNITURE.

1,306,268.

Specification of Letters Patent. Patented June 10, 1919.

Application filed June 4, 1918. Serial No. 238,090.

To all whom it may concern:

Be it known that I, FRED W. McARDLE, a citizen of the United States, residing at Boston, in the county of Suffolk and State 5 of Massachusetts, have invented certain new and useful Improvements in Furniture, of which the following is a specification.

My invention relates to furniture and particularly to furniture of that class that is 10 made up of adjustably connected parts so that it can be converted from an article of furniture of one kind to an article of furniture of another kind.

The object of my invention is to provide 15 an article of furniture of the class described, and particularly, to provide an improved structure of simple and advantageous construction which can be adjusted into the form of either a chair or a couch.

20 To these ends my invention consists of a convertible article of furniture of the character described having the peculiar features of construction and mode of operation set forth in the following description and particularly pointed out and defined in the 25 claims at the close thereof.

In the accompanying drawings:

Figure 1 is a central longitudinal sectional view of a chair constructed in accordance 30 with my invention.

Fig. 2 is a plan view of a portion of the chair shown in Fig. 1.

Fig. 3 is a partial front view of the chair shown in Fig. 1 with the back thereof in up- 35 standing position.

Fig. 4 is an enlarged sectional detail of the front portion of the chair shown in Fig. 1.

Fig. 5 is a view similar to Fig. 4 but showing the parts in other positions.

40 Fig. 6 is a front elevation of some of the parts shown in Fig. 5.

Fig. 7 is a detail, in plan, of some of the parts shown in Fig. 4.

Figs. 8 and 9 are sectional details illustrating the construction and operation of the 45 back portion of the chair.

Herein I have shown my invention as embodied in a chair of that type known as a Morris chair, and as comprising a rectangular seat frame consisting of a front bar 1, a rear bar 2, and two side bars 3 and 4. These four bars are fastened at their ends to four upright posts 5 whose lower portions rest upon the floor and serve as legs, and 55 whose upper portions have secured to them the side arms 6. The side arms 6 are pro-

vided at their rear ends, as usual, with racks 7 to receive the end portions of a removable back supporting rod 8.

The back of the chair comprises a rectangular wooden frame consisting of two side-bars, one of which is shown at 9, and two end bars 10 secured at their ends to the ends of the side bars. This back frame is pivotally connected with the rear cross-bar 2 of the seat frame by hinges 11 and can be swung on said hinges into the horizontal position shown by full lines in Fig. 1, or into an upstanding rearwardly inclined position where it may be secured by the removable rod 8, the position of the latter on the racks 7 determining the angle of inclination of the back.

Near each end of the back frame 9-10 there is a cross-bar 12 and to these two cross-bars are fastened the opposite ends of a wire mattress 13 which supports an upholstery mattress or cushion 14. Within the seat frame 1, 2, 3, 4 are arranged cross-bars 15 and 16 fastened at their ends to the side bars 1 and 3 of said seat frame. These bars 15 and 16 support springs 17 which in turn support an upholstery mattress or cushion 18.

In carrying out one feature of my invention I provide each side bar 9 of the back frame with a leg 19 having one end thereof pivotally connected with its side bar as at 20. To each leg 19 is pivotally connected one end of a slide bar or rod 21 arranged within the back frame alongside of the adjacent side bar thereof and supported near its middle by a lug 22 projecting from said side bar, through which it loosely extends. The opposite end 23 of rod 21 extends through a hole in the cross-bar 10 hinged to bar 2 of the seat frame so that it is supported against lateral movement. Mounted upon the rod 21 is a spring 24 abutting at one end against a collar 25 fast on rod 21. Spring 24 acts through collar 25 to yieldingly urge rod 21 endwise toward the seat frame so that when the back frame occupies either of its upstanding positions the inner end 23 of said rod, see Fig. 7, projects beyond the cross-bar 10 of the back frame, the spring 24 acting through said rod to hold the leg 19 in retracted inoperative position within the back frame as indicated by dotted lines in Fig. 1, where it is out of sight and out of the way. When the back is lowered to its horizontal position as shown by full lines in Fig. 1, the end 23 of rod 21 comes

against the cross-bar 2 before the downward movement of the back is completed and during the last portion of said movement after the rod has thus been brought into engagement with said cross-bar, the rod is moved endwise relatively to the back toward the pivot 20 thereby swinging the leg on said pivot into a perpendicular position relatively to the back frame so that its lower 10 end rests upon the floor.

As means for automatically locking the leg in its perpendicular operative position when the back is thus lowered I provide two links 26 and 27 connected at 28 by a knuckle 15 joint and pivoted, respectively, to the leg 19 and side bar 9. When the leg 19 occupies the position indicated by dotted lines in Fig. 1 the two links 26 and 27 occupy positions within the back frame and alongside 20 of each other but are free to swing apart into their leg locking positions as the leg is swung outwardly during the lowering movement of the back. When the back is swung upwardly from its horizontal position the 25 leg 19 may remain locked in its projected position by the links with spring 24 under compression, but after placing rod 8 in position on its racks 7, a slight tap on the links 26 and 27 opposite the knuckle joint 28 releases the leg which is immediately thrown 30 inwardly by spring 24 acting through rod 21, into its retracted position within the back frame.

As will be clear, the automatically operating means just described for supporting the outer end of the back when the latter occupies its lowermost, or horizontal, position is of such construction that it can be applied, if desired, as an attachment to the ordinary 40 Morris chair now in common use, thereby rendering the latter convertible into a couch.

It has been proposed to construct or provide a Morris chair with a foot rest adjustably connected with the seat of the chair so 45 that it can be shifted back and forth and occupy either an operative position forward, or in front of, the seat or an inoperative position beneath said seat. My present invention contemplates a foot rest of this kind but 50 one which also can be adjusted into a second operative position at the front end of the seat to serve as an elevated head support or pillow. To this end I provide a slide 29 beneath the chair seat supported by two 55 channel irons 30 secured to the under sides of the cross-bars 1 and 16 of the seat frame. This slide 29 has an extension piece or section 31 pivotally connected with its forward end by hinges 32, said section 31 being 60 adapted to be adjusted on said hinges so as to occupy a position on top of the forward end of slide 29 as shown in Figs. 1 and 4, or to be swung forward into the position shown in Fig. 5. Section 31 carries a pivoted latch 65 33 extending through a hole 34 formed in

slide 29, said latch being provided with a plurality of teeth to engage with the portion of the slide at the side of said hole as shown in Figs. 1 and 4, to hold section 31 against swinging outwardly and upwardly on hinges 70 32, the plurality of teeth on said latch providing for different angular positions of the section 31 relatively to slide 29 as will be clear by reference to the dotted lines in Fig. 1. This latch 33 is necessary for the reason 75 that there is a preponderance of weight on section 31 forward of pivot hinges 32 when section 31 occupies the full line position in Fig. 1.

To one side of the section 31 is secured 80 a metal bracket 35 and to one end of this bracket is pivotally connected, as at 37, a foot and head rest 36. The opposite end of the foot and head rest is shown in Fig. 1 as supported by a prop 38 which in turn is 85 supported at its lower end by a slotted arm 39 projecting forwardly from, and integral with, the base portion of the bracket 35. The prop 38 is pivotally connected with the under side of the rest 36 and occupies the 90 slot of the arm 39, said prop being formed with the studs 43 and 44 co-operating with lugs 40 and 41 projecting from the arm into the slot thereof. When the rest 36 occupies operative position either as a head rest or as 95 a foot rest, the section 31 is in position upon the top of the front end of the slide 29 as in Fig. 1. To adjust the rest so as to serve as an elevated head rest the front side thereof is swung upwardly on the pivot 37 and 100 the prop 38 placed in position with either studs 43 or 44 resting on the lugs 41 so that the forward side of the rest is held elevated by the prop well above the plane of the chair seat. To adjust the rest 36 so as to serve as 105 a foot rest the prop 38 is swung rearwardly on its pivot to permit the forward side of the rest to be lowered onto the arm 39, said prop then occupying the position in the slot shown in Fig. 4. With the rest in this position it 110 can be adjusted forwardly and rearwardly to position it as desired relatively to the chair seat by moving slide 29 along its supporting ways 30. When desired the rest may be secured in an outwardly inclined or 115 tilted position, as indicated in Fig. 1, by means of latch 33. A plurality of studs are provided on the prop 38 so that rest 36 may be fixed at different elevations. The lugs 40 are provided so that when the section 31 is 120 swung forward into the position shown in Fig. 5 from the position shown in Fig. 4, and slide 29 is shoved rearward to carry the rest 36 under the chair seat, the engagement of the free end of the prop 38 with the underside 125 of slide 29 together with the engagement of the studs 43 with lugs 40, will serve to hold the rest 36 against swinging downwardly on pivot 37, while the cross-bar 1 acts to hold section 31 against being lifted on pivot 130

hinges 32. In other words, the prop 38 cooperates with the lugs 41 to support the rest 36 at the desired height when the rest is in operative position, and with lugs 40 and the 5 under side of the slide 29 to hold the rest snugly up against the arm 39 when the rest is swung under said slide into its inoperative position. When the rest occupies this 10 inoperative position the slide 29 can be shoved inwardly to place the rest under the seat as will be clear.

An ornamentally shaped laterally extending bar 446 of wood may be secured to the free end of the section 31 to cover or hide 15 most of the parts of the head and foot rest device when the latter occupies its retracted inoperative position shown in Fig. 5.

What I claim is:

1. A chair of the character described, having in combination, a seat; legs connected with said seat; a back adjustably connected with said seat; a slide movably mounted beneath said seat; an extension for said slide pivotally connected with the forward end 25 thereof so as to provide for its being swung forward into inoperative position in front of the end of the slide or backward into operative position on top of said slide; a rest pivotally connected near one side thereof to said extension, and means adjustably connecting the other side of the rest with said extension, said means serving also to hold said rest against swinging downward on its pivot when said extension occupies its 30 inverted inoperative position in front of said slide.

2. A chair of the character described, having in combination, a seat; legs connected with said seat; a back adjustably connected 40 with said seat; a slide movably mounted beneath said seat; an extension for said slide pivotally connected with the forward end thereof so as to provide for its being swung forward into inoperative position in front 45 of the end of the slide or backward into operative position on top of said slide; a rest pivotally connected near one side thereof to said extension, and means adjustably connecting the other side of the rest with said 50 extension, said means also engaging the slide to hold said rest against swinging downward on its pivot when said extension occupies its inverted inoperative position in front of said slide.

55 3. A chair of the character described, having in combination, a seat; legs connected with said seat; a back; a slide movably mounted beneath said seat; an extension for

said slide pivotally connected with the forward end thereof so as to provide for its being swung forward into inoperative position in front of the end of the slide or backward into operative position on top of said slide; a rest pivotally connected near one side thereof to said extension, and a prop-latch 60 pivotally connected with said rest and adjustably engaging said extension to support the opposite side of the rest, said prop-latch engaging the slide so as to hold the rest against swinging downward on its pivot 65 when the extension occupies its inverted inoperative position.

4. A chair of the character described, having in combination, a seat; legs connected with said seat; a back; a slide movably mounted beneath said seat; an extension for said slide pivotally connected with the forward end thereof so as to provide for its being swung forward into inoperative position in front of the end of the slide or backward into operative position on top of said slide; a rest pivotally connected near one side thereof to said extension; a prop-latch pivotally connected with said rest and adjustably engaging said extension to support the opposite side of the rest, and another latch for adjustably holding said extension in operative position above said slide against the effects of downward pressure on the rest. 75

5. A chair of the character described, having in combination, a seat; legs connected with said seat; a back; a slide movably mounted beneath said seat; an extension for said slide pivotally connected with the forward end thereof so as to provide for its being swung forward into inoperative position in front of the end of the slide or backward into operative position on top of said slide; a bracket arm projecting forward from said extension when the latter occupies 90 its operative position on top of said slide, said bracket arm being formed with a slot having lugs projecting from the side walls thereof; a rest pivotally connected to said arm, and a prop-latch pivotally connected 95 with said rest and occupying the slot of said arm, said prop-latch cooperating with said lugs to adjustably support said rest when the latter is in position for use, and also cooperating with said lugs and the slide to hold said rest against swinging downward on its pivot when said extension occupies its inverted inoperative position. 100

In testimony whereof I have affixed my signature.

FRED W. McARDLE.
